RECORD CONTROLLED ADDRESS TYPE
PRINTING MACHINE

Walter T. Gollwitzer, Euclid, Ohio, assignor to
Addressograph-Multigraph Corporation, Wil-
mington, Del., a corporation of Delaware

Original application May 27, 1946, Serial No.
672,581, now Patent No. 2,605,699, dated Au-
gust 5, 1952. Divided and this application Oc-
tober 12, 1951, Serial No. 251,085

7 Claims. (Cl. 101—96)

1

This application is a division of my co-pending application, Serial No. 672,581, filed May 27, 1946, issued as U. S. Patent No. 2,605,699 on August 5, 1952.

This invention relates to a printing machine and more particularly to a printing machine which is adapted to print changeable data such as names and addresses, or variable data, such as numerical quantities, amounts of money and the like. More particularly, this invention relates to machines for printing data of the aforesaid character under the control of record members such as perforated cards or other control devices which are fed into a control position seriatim in synchronism with the feeding of sheets or the like to a printing station.

In certain types of business enterprise, particularly where printed forms embodying changeable and/or variable data must be issued periodically, it is highly advantageous to effect such printing automatically under the control of record members such as perforated cards which determine the positioning of printing members for each sheet or article printed.

It is an object of my invention to print each sheet, envelope or other article or document under the control of a record member which is peculiar to that document by sensing such record member with mechanical devices which are so constructed as to control the setting of variable or changing printing elements at the printing station.

A further object of the present invention is to connect changeable or variable printing members to sensing mechanisms of the character mentioned above in such a manner that operation is accurate and can be carried on at a relatively high rate of speed. For the purpose of controlling such printing members the present invention utilizes certain sensing means which are more particularly described and are claimed, per se, in my co-pending application, Serial No. 663,467, filed April 19, 1946, now United States Patent No. 2,508,603, patented May 23, 1950.

A further object of my invention is to combine variable printing members with sensing means of the type described in my aforesaid co-pending application in such a manner as to insure rapid and efficient operation properly timed with the feeding of control members such as perforated cards through the sensing position.

Other and further objects of the present invention will be apparent from the following description and claims and are illustrated in the accompanying drawings which, by way of illus-

2

tration, show preferred embodiments of the present invention and the principles thereof and what I now consider to be the best mode in which I have contemplated applying these principles. Other embodiments of the invention embodying the same or equivalent principles may be used and structural changes may be made as desired by those skilled in the art without departing from the present invention and the purview of the appended claims.

In the drawings:

Fig. 1 is a front elevation of a printing machine embodying features of my invention;

Fig. 2 is a plan view of the printing machine, with certain parts broken away and showing a feeding mechanism that may be used with a printing machine embodying the features of the present invention;

Fig. 3 is a vertical sectional view from front to rear of the machine taken substantially on the line 3—3 of Figs. 1 and 2;

Fig. 4 is a plan view of a perforated card which may be used as a control member in the printing machine;

Fig. 5 is a horizontal sectional view showing the upper part of the machine, this view being taken substantially on the lines 5—5 of Figs. 1 and 6;

Fig. 5A is a fragmentary elevational view of certain printing elements, parts being shown in section;

Fig. 6 is a vertical sectional view taken across the rear part of the machine and looking forward, substantially along the line 6—6 of Fig. 5;

Fig. 6A is a fragmentary elevational view of operating elements for part of the printing mechanism, taken substantially on the line 6A—6A, Fig. 6;

Fig. 7 is a left side elevational view of the machine, certain parts being shown in section and this view being taken substantially along the line 7—7, Fig. 2;

Fig. 8 is a detail view of a modified driving arrangement shown in the upper right hand part of Fig. 7;

Fig. 9 is a detail view of the modified driving arrangement taken at right angles to the view shown in Fig. 8 and substantially along the line 9—9, Fig. 7;

Fig. 10 is an enlarged fragmentary elevational view similar to the left-hand part of Fig. 7, being on a somewhat larger scale and illustrating certain modifications of certain elements;

Fig. 11 is a vertical sectional view through a

feeding mechanism for cards or the like taken substantially on the line 11—11, Fig. 2;

Fig. 12 is a view similar to Fig. 11 but showing certain parts in changed positions;

Fig. 13 is a transverse vertical section through the feeding mechanism shown in Figs. 11 and 12, this view being taken substantially along the line 13—13, Fig. 2;

Fig. 14 is a horizontal sectional detail view taken substantially on the line 14—14, Fig. 13;

Figs. 15, 16, 17 and 18 are each transverse sectional detail views showing various parts of the feeding mechanism for cards or the like, these views being taken substantially along the lines 15—15, 16—16, 17—17, and 18—18, respectively, on Fig. 2.

The printing mechanism which embodies my invention is mounted upon a suitable supporting base 11, as best shown in Figs. 1, 3 and 7. Supported on the base 11 are vertically upstanding posts or column members 12, 13 and 14 for supporting upper frame members and various operating parts. A driving motor 15 which may be an electric motor of any appropriate size and type is secured by suitable means to a supporting block 16 which may be mounted on the base 11.

Above the base 11 and spaced therefrom by the vertical columns 12, 13 and 14 are a pair of horizontal parallel frame members 17. At the rear of the machine, shown at the left in Fig. 7 and at the right in Fig. 3, an upper frame structure is mounted above the columns 13 and 14, this structure comprising a pair of parallel spaced vertical plates 18 and 19 which mount various operating elements to be described hereinafter. The plates 18 and 19 may be secured to the posts or columns 13 and 14 by any suitable means such as screws or bolts 20.

The rear ends of the bars 17 are secured to the plates 18 and 19 by any suitable means such as the screws 21 and 22. A horizontal bar 23 extends between and is rigidly secured to the forward ends of the bars or beams 17. At its midpoint the bar 23 is mounted on the top of the vertical post or column 12 to which it is secured as by a screw 24.

Extending along the front of the machine is a feed table for perforated cards or the like which are to be fed into a sensing position where, through sensing means and other connecting elements to be described hereinbelow, the printing members are set selectively into printing positions. After the cards are so sensed they are fed out of sensing position along the same feeding table by means and in a manner to be described hereinafter. The feed table is designated generally by the reference character 30 and it comprises a pair of spaced horizontal bars 31 and 32 which extend parallel with the front of the machine and across the beams or frame members 17 to which they are secured in any appropriate manner. A flat member 33 which is mounted on and secured to the bars 31 and 32 constitutes the table surface, as best shown in Figs. 15 to 18.

At the right end of the table, as seen by an operator facing the machine and as best shown in Fig. 1, means are provided for supplying cards or similar control members C which are provided with indicia to be sensed. As shown in Fig. 4, such cards or control members may be provided with perforations at selected positions to indicate indicia which is to be set up in the printing elements of the machine. It will be understood, however, that the indicia might be in the form of protuberances or other distinctive elements

formed on a flat or substantially flat member and being capable of sensing by mechanical sensing elements such as those described in detail in my aforesaid Patent No. 2,508,603.

As shown in Fig. 1 and in the left-hand part of Fig. 2, the sensing station is located about the middle of the table, in the length thereof, and a receiving hopper 33A in which the cards or like articles after being sensed at the sensing station are collected is provided at the delivery end of the table.

The means for advancing the article to be fed from the supply magazine, generally indicated at M in Fig. 1, to the sensing station, are described in detail in my aforesaid application Serial No. 672,581, now U. S. Patent No. 2,605,699, and therefore a brief description only of such means will herein be given.

A rotatably mounted shaft 34 is mounted above the table 30 and in spaced parallel relation therewith in suitable bearings 35 and 36. This shaft extends substantially the full length of the table and controls and operates various mechanisms associated with the feeding and advancing of the control cards C. At its right end, as shown in Fig. 1, the shaft 34 carries a disc 37 which bears an eccentric crank pin 38. The disc 37 is secured to the shaft 34 for rotation therewith.

The eccentric pin 38 is connected through a series of linkages to an oscillatable bell crank 43 having a slotted end for the reception of a roller 49 carried on a plate 51. Plate 51 is provided with a flanged member 52 which is free to slide in the guideway 54. Oscillation of the bell crank, therefore, imparts reciprocatory movement to the plate 51.

As best shown in Fig. 11, plate 51 has one end partly disposed in the supply magazine and beneath the trailing edges of the cards C stacked therein. A plate in the form of a leaf spring 56 is fixed at one end to the reciprocable plate 51 and is provided with a stud 58, extended through an opening provided in plate 51 in position to engage the cammed end of slot 61. It will be clear from Fig. 11 that the free end of plate 56 is adapted to abut against the trailing edge of the lowermost one of the stacked cards C to feed the same between the rollers 85 and 101, as shown in Fig. 12. Once plate 51 slides along the bottom of the magazine to an extent that stud 58 engages the cammed end of slot 61, plate 56 is urged into a more effective feeding engagement.

In order to assure that only the lowermost one of the stacked cards C will be fed to the feed roller 85 and the idler roller 101, a vertical bar 65, Figs. 2 and 14, is disposed within the supply magazine. This bar is triangular in cross section and configured complementary to the notch 67 provided in one edge of a card as C, Figs. 4 and 14. In this manner, the cards as C can be positioned in the magazine only when they are properly aligned relative to bar 65. As shown in Fig. 13, bar 65 terminates short of the bottom of the magazine by an amount equal to or very slightly greater than the thickness of a card C and consequently only the lowermost one of the cards will have its notch out of engagement with bar 65 and thus be in position to be fed from the magazine.

In order that the cards will always be firmly positioned against the forward end of the supporting plate 51, for engagement with the feed plate 56, a weight 71 is provided.

As a further assurance to feeding of the lowermost card only, a flexing device 75, substantially in the form of a U-shaped bar as shown in Fig.

15, is provided adjacent the forward end of the supply magazine. A leaf spring 76 normally tends to urge bar 75 downward in the slot 82 and out of the path of an advancing card C as shown in Fig. 12. In order that bar 75 can be shifted vertically upward relative to the slot 82 to flex the stacked cards as shown in Fig. 11, a cam 77 is fixed to shaft 34 for rotation therewith as shown in Fig. 15, and this cam has a flat portion 79 which allows bar 75 to be lowered by spring 76.

As shown in Figs. 2 and 16 a first feed roller 85 is mounted in a position to engage the advancing end of the bottom card as it is pushed out of the stack by the feeding plate 56 in the manner described above. The feed roller 85 is mounted on a sleeve 86 for rotation therewith, the sleeve 86 being mounted on a non-rotatable shaft 87. At its forward end the shaft is secured to a leaf spring 82 which is anchored to the bar 77 in the same manner as the leaf spring 76 which mounts the flexing bar or member 75. A belt pulley 89 is secured to the sleeve 86 for driving the roller and a belt 90 which passes about this pulley is driven by a pulley 91 supported on a jack shaft 92 mounted in a bracket 93, as shown in Figs. 1 and 3. The pulley 91 is secured to a larger pulley 94 which is driven by a belt 95 which passes about a pulley 96 on the motor 15. The belt 90 also passes forward, as shown in Fig. 1, about another pulley 97, Fig. 1, which drives another feed roller to be described presently. Returning, the belt 90 passes over a small idler pulley 98 which is mounted freely on the shaft 87 beside the pulley 89. By the means just described, the feed roller 85 is continuously driven but it is effective to advance a card only when it is in the lowered position, as shown in Fig. 16, that is, when the flat portion of a cam 99 on shaft 34 is disposed so as to lower the feed roller 85 into cooperating position with respect to a small idler roller 101 which is rotatably mounted on a bracket 102 beneath the table top and has its periphery extending through a slot 103 in the table top to a position substantially flush with or very slightly above the table surface.

To guide the cards C as they advance, undercut guide bars 104 and 105 are mounted on the feed table, one being suitably fastened thereto at either side of the feed path so as to keep the cards in proper alignment. The front and rear edges of the cards ride in the grooves 106 and 107, respectively, and thus the cards are presented squarely to the sensing station, the guide bars 104 and 105 being spaced apart a distance equal to the width of a control card C.

The feed roller 85 in cooperation with the underlying idler 101, Fig. 11, advances a card C into sensing position under a series of sensing elements or teeth 110, each of which is carried by a sensing bar 111. These bars are specifically described in my aforesaid co-pending application, Serial No. 663,467, now U. S. Patent No. 2,503,603, and are shown in outline in Figs. 3 and 7. By means described more particularly in my aforesaid co-pending application and including the rack members 112 and 113, Fig. 3, the sensing bars are operated to move across the surface of each card as it is in sensing position and to sense perforations or other indicia therein or thereon to position the arcuate rack members 113 which in turn position printing characters in a manner to be described more fully hereinbelow. Upon the sensing element 110 encountering an indicium on the card or other record member C, the sensing

bar 111 rocks in a vertical plane to engage locking means described below.

During the time that sensing is taking place, as previously described above, the advance end 5 of the card C to be sensed is positioned against a front stop or positioning member and under another feed roller which at an appropriate time is lowered to carry the card out of sensing position and deliver it to the receiving hopper 33A. 10 As shown in Fig. 17, this other feed roller is indicated by the reference character 115 and it is indicated by the reference character 115 and it is mounted on a sleeve 116 which in turn is carried by a shaft 117 secured by leaf spring 117S 15 to the front bar 77 in the same manner as feed roller 85, previously described. The pulley 97, which is driven by belt 90 in the manner described above, rotates the sleeve 116 and the feed roller 115. As shown in Fig. 18 a stop finger 118 20 is positioned in the path of the advancing cards at a point where it will hold them properly and accurately in sensing position during operation of the sensing fingers 111. This finger comprises a vertical plate mounted on a horizontal bar 119 carried by a leaf spring 121 also secured to the front bar 77. The feed roller 115 and the stop finger 118 are raised and lowered at appropriate times in the feeding cycle by cams 122 and 123, respectively, mounted upon the shaft 34. It will thus be seen that all of the mechanisms which feed the card from a stack of cards to and through sensing position and into a receiving hopper are controlled by elements operated from the shaft 34. A card or control device C, to be sensed, is retained in sensing position while the sensing fingers 111 are slid across the face thereof. When an indicium, such as a perforation in a card, is sensed the sensing finger immediately rocks slightly and is locked against further movement across the card. This locking is accomplished by means and in a manner fully described in my aforesaid co-pending application, Serial No. 663,467. Locking the sensing bar against movement obviously positions the racks 122 and 123 in a definite position.

Shaft 34, which controls the various feeding elements described above, has keyed thereto a bevel gear 125 at its left end as seen in Fig. 1. This gear meshes with a bevel gear 126 on a shaft 127 which extends rearwardly of the machine. The shaft 127 is driven in a manner to be described presently, so that shaft 34 is rotated in proper timed relation with operating elements of the printing unit per se. In this manner, and as 55 fully described hereinbelow, the feeding of cards or the like C is accurately synchronized with printing operations.

As shown in Figs. 1 and 2, the bevel gears 125 and 126 are of the same size so that the shafts 34 and 127 rotate at the same speed. With this arrangement a card is fed for each impression of the printing unit, to be described hereinafter. However, for some purposes it is desirable to print the data sensed more than once as, for example, on the body and stub of a check, receipt, utility bill or the like. In such cases it is desirable that the gear ratio be changed so that only one card will be fed to sensing position for every two or three, or possibly more operations 65 of the printing mechanism.

Accordingly, and as shown in Fig. 7, this arrangement may be modified to provide slower operation of the feed mechanism with respect to certain other parts of the machine including 70 the printing mechanisms. As shown in Figs.

8 and 9 the shaft 34 carries a relatively large spur gear 131 which meshes with a small spur gear 132 carried by a jack shaft 133. In this instance the bevel gear 125', carried by the jack shaft just mentioned, meshes with a similar bevel gear 126' on the rearwardly extending shaft 127. Shaft 127 is driven by bevel gears 135 and 136, the latter being mounted on the end of a cam shaft 137 which is carried by the frame members 18 and 19 previously described. Shaft 137 operates the printing mechanism in a manner to be described more fully below and it carries a large spur gear 138 which, as described hereinbelow, may be operably connected with the shaft through a clutch. As shown in Fig. 7, gear 138 meshes with a small spur gear 139, mounted on a jack shaft 141. Integral with the small spur gear 139 is a larger gear 142 which meshes with a small spur gear 143 mounted coaxially with and driven by a pulley wheel 144. The pulley is driven by means of a belt 145 from a small pulley 146 on the motor 15. By the means just described, various mechanisms of the machine including the printing unit and the card feeder are driven and it will be seen that a positive gear ratio is established between the feed mechanism and the printing mechanism which is operated by cams on the shaft 137 in a manner to be described hereinbelow. The feed rollers 85 and 115 which advance the cards C from station to station are not synchronized with the other parts of the machine, such synchronization not being necessary because the lowering of these rollers into cooperation with the cards is accurately timed by cams on shaft 34.

Referring now to Fig. 3, it will be noted that the arcuate racks 113, previously mentioned as cooperating with racks 112 to move the sensing bars 111 to sensing position, are integral with or secured to printing sectors 151. In that form of my invention shown in Figs. 1 to 18, inclusive, there are as many sensing bars 111 as there are rows of data or data positions on a card C to be sensed. Hence there are a similar number of rack members 113 and printing sectors 151 and each printing sector is adapted to be selectively positioned so as to present a desired character in printing position dependent upon the position at which the sensing bar 111 comes to rest in sensing movement across a card C. As mentioned above and shown in Fig. 3, and as more fully described in my aforesaid co-pending application, Serial No. 663,467, now U. S. Patent No. 2,508,603, the sensing bars 111 slide across the surface of a card until they encounter a perforation therein whereupon they drop into engagement with a notch in a serrated plate 152. This plate is provided with accurate serrations and is accurately positioned in the machine. Hence when a sensing bar comes into a stop position the printing sector 151 is positioned with a high degree of accuracy. For example, the printing sector 151 may carry a set of digits therein from "0" to "9." A perforation in the card C may represent any one of these digits and when it is sensed the sensing bar 111 is locked in an accurately determined position so that the printing member 151 is also accurately set to dispose the desired printing character below an inked ribbon IR.

Control devices, such as perforated cards C, are subject to variations in size and it is not always possible to locate indicia such as perforations therein with a high degree of accuracy.

Also, as cards of this character, and particularly paper cards, are handled repeatedly and passed through sensing mechanisms and other devices, the perforations frequently become distorted or enlarged. Since it is desirable that minor inaccuracies in the location and form of indicia on cards as C be not transmitted to printing members controlled by sensing devices, separately controlled locking means, other than the perforation in the card itself are provided. Thus the sensing tooth 110, on the end of a bar 111, which drops into a perforation on card C encounters an accurately located serration on the plate member 152 underlying the card C, which determines accurately the point at which the sensing bar 111 will be stopped in its transverse sensing movement. Minor inaccuracies in the location of the perforations in the card C have no effect on the accuracy with which the sensing bar is finally located, unless the inaccuracy is so great as to cause the sensing tooth on a bar 111 to engage the wrong serration in which case of course the card should be destroyed and a new one substituted.

The serrations shown on the lower side of the bars 111, as in Fig. 3, cooperate with other locking means, the details of such construction and operation being fully described in my aforesaid co-pending application, Serial No. 663,467, now U. S. Patent No. 2,508,603.

It is important to note that the positioning of the sensing bars and of the printing elements which they control is only under general control of the indicia carried by the cards C, being under the specific control of the locking elements briefly described above and more fully described in the application just mentioned. In other words, an indicia, as a perforation in a card C, determines what printing character will be selected, but the exact movement of that printing character to a precise printing position is determined by the means which accurately locate and lock the sensing bar, as 111, in its final position. Direct connection between the sensing bar 111 and the printing member 151 makes sure that the printing member will be located with the same degree of accuracy as the sensing bar, the teeth of racks 112 and 113 being accurately formed for this purpose.

Another advantage of this construction, aside from the accuracy which printing members may be selectively positioned, results from the fact that the sensing bars are finally positioned by mechanical elements rather than by the cards C.

Since these elements have appreciable mass, even though they may be made very light, cards of paper or the like would be damaged and rapidly destroyed if they were required to stop in sensing position the bars 111 moving under the force of springs as 175. Instead, the shock of stopping the bars and parts associated therewith is taken by the serrated plate 152 and other locking means and the cards C are saved from injury.

Above the inked ribbon IR, and aligned with each of the printing sectors 151, there is disposed a printing platen element 153 carried by a bell crank 154 which is mounted pivotally upon a shaft 155 in the upper rear portion of the side frames 18 and 19. There are as many platen elements 153 and bell cranks 154 as there are printing sectors 151, each platen element being individually movable to press an article to be printed, such as a sheet of paper, against the inked ribbon, causing an impression to be taken

from the printing characters disposed beneath the inked ribbon by the sectors 151.

The bell crank levers 154 which carry the platen elements are each provided with a rather strong tension spring 156 connected between the bell crank and a stationary rod 157. Extending above the bell cranks 154 is a hood or shield 158 which carries a comb member 159 at its forward end, disposed so as to keep the bell cranks 154 properly separated and the platen elements 153 each aligned with its respective printing sector 151.

A substantially flat and horizontal printing table 160, Figs. 1, 2, 3, 7 and 10, is mounted on the frame members 18 and 19 at a height substantially flush or level with the tops of the printing sectors 151. This table is provided with an opening 161 through which the printing characters on the sectors 151 and the inked ribbon IR are exposed for cooperation with the platen elements 153. The table 160 supports the hood or shield 158 and comb member 159 mentioned above. Guide means 162 and 163 are provided for sheets, envelopes or other articles which are fed along the table to be printed with the data represented or controlled by the indicia on the cards or control members C. Normally the printing platens are held in raised position, as shown in Figs. 3, 7 and 10 by a bail member 164 carried by an arm 165 pivoted on a shaft 166. This bail member 164 contacts the lower ends of the bell cranks 154, as clearly shown in Fig. 3. As fully described in my aforesaid co-pending application, an arm 165A extends from the shaft 166 to a cam 167 carried by the shaft 137, Fig. 5A, and at appropriate times after the printing sectors have been set selectively in printing position according to data sensed on the control cards C the cam permits the arm 165A to swing clockwise as shown in Figs. 3 and 5A, for example, and the bail member 164 swings downwardly in a slot 167 provided in each of the frame members 18 and 19. This permits the springs 158 to draw the bell cranks 154 which carry the platen elements downwardly quickly and forcibly so as to produce a printing impression on the lower side of the sheet or other article disposed over the printing sector 151 and lying between the guide members 162 and 163 on top of the upper table surface 160 which supports the article being printed. The platen elements are shown in printing position in Fig. 5A.

Means are provided for rotating the printing sectors 151 and the racks 113 which are integral therewith in both directions about the shaft 171 on which they are freely pivoted. Since the racks 112 are integral with the sensing bars 111 and are in mesh with the racks 113, rotary movement of the printing sectors is accompanied at all times by longitudinal sliding movement of the sensing bars 111. As best shown in Figs. 3 and 5A a bail member 172 is mounted on arms 173 fixed against rotation on the shaft 171. The arms 173 also carry a transverse rod 174. A tension spring 175 is connected between each of the printing sectors 151 and the rod 174.

Referring now to Fig. 6A, the shaft 171 has affixed thereto, as by set screw 176, a two armed lever 177 carrying at the end of each arm a cam follower roller 178. Each of the rollers 178 is adapted to cooperate with one of a pair of conjugate cams 179 and 180, carried by and fixed to the shaft 137. By the means just described the shaft 171 which carries the arms 173, bail 172 and rod 174, is rocked in alternate directions at appropriate times. When the shaft is rocked

clockwise, as shown in Figs. 3 and 6A, the bail 172 is withdrawn from contact with the rear edges of the printing sectors 151 and the springs 175 are tensioned to urge the printing sectors to rotate clockwise also. This causes the sensing bars to move forward, the sensing element at the extreme front end of each bar sliding across a card C in sensing position (not shown in Fig. 3) until a perforation or other indicia borne by the card is encountered. As briefly explained hereinabove and as more fully described in my aforesaid co-pending application, Serial No. 663,467, now U. S. Patent No. 2,508,603, the sensing bars are stopped in accurately defined positions and the various printing sectors likewise are positioned selectively, according to the data sensed, to print when the platens 153 are lowered to strike the upper surface of an article to be printed.

The printing sectors are retained in printing position by means more fully described in my aforesaid co-pending application, and including the locking elements 182 and 183, Fig. 3, until printing is accomplished. Thereafter, the conjugate cams 179 and 180, Figs. 6A, return the shaft 171 and arms 173 to their normal or zero positions counterclockwise, as seen in Figs. 3 and 6A, and the bail member 172 restores the printing sectors 151 and the sensing bars 111 to their zero positions. As each new card C to be sensed is fed into sensing position, these operations are repeated.

The platen elements 153, carried by bell crank levers 154, as previously described, are quickly withdrawn from impression position after printing is accomplished, this occurring before the printing sectors 151 are restored to their zero positions in the manner just described. In case it is desired to print the same data on separate sheets, or on different parts of the same sheet, the card C is retained in sensing position during a plurality of cycles of the shaft 137. The arrangement described hereinabove in connection with Figs. 8 and 9 provides for operation of shaft 137 a plurality of times while the card feeding mechanism is being operated only once. The number of operations for each card is obviously determined by the ratio of the spur gears 131 and 132. Where the ratio is to be one to one, the spur gears are eliminated and the drive is directly from shaft 127 to shaft 34 through bevel gears 125 and 125.

Any suitable means may be provided for feeding sheets to be printed along the table 160 over the opening 161 and between the guides 162 and 163. A mechanism suitable for this purpose is described in detail in my Patent No. 2,342,190 issued February 22, 1944. In those instances where a plurality of impressions are to be taken on a single sheet, suitable feeding means for advancing the sheet step by step may be provided. Since the feeding means for single printed sheets, or for advancing sheets step by step through the printing means of the present invention form no part of such invention, description thereof is unnecessary.

Means are provided in my improved printing machine for advancing the inked ribbon IR step by step so as to present a new portion thereof in printing position after each operation of the machine as is well known in the art. As shown in Figs. 6 and 6A, these means include an arm 191 secured to the shaft 171 as by a set screw 192 for rotation therewith. A substantially vertical link 193 has its lower end engaged in an opening in the end of arm 191 and its upper end

is pivotally connected with one arm 194 of a bell crank pivotally mounted on a stud 195 secured to a part of the frame. The other arm 196 of the bell crank terminates in a short rack portion 197 which engages cooperating teeth on a block 201 secured by a set screw 202 to a transversely slidable rod 203. Near each end thereof the rod 203 carried a forwardly projecting pawl member 204 affixed non-rotatably to said bar as by a set screw 205. A tension spring 206 is attached to one of the pawl members, the upper ends of said spring being secured to a frame portion to urge said pawls upwardly into cooperation with ratchet wheels 207 which are secured non-rotatably to reels 208 for the inked ribbon IR. The reels 208 and ratchets 207 may be supported by suitable bolts 209 secured to an appropriate frame member. Reversing mechanism is provided as well known in the art, description thereof being unnecessary. When the shaft 171 is oscillated by the conjugate cams 179 and 180, the link 193 causes the bell crank 194, 196 to slide the rod 203 back and forth and the pawls 204 engage one or the other of the ratchets 207 to advance the ribbon in one direction or the other, depending upon the position of the reversing mechanism.

A hand wheel 210 is mounted to rotate with shaft 137 during normal operation and provide a manual means by which the printing mechanism may be operated when desired.

Manual means are provided, also, for locking the printing platens in their raised positions when it is desired to operate shaft 137 without printing. As shown in Figs. 3, 6 and 10 a two-armed lever 211 is pivoted on a stud 213 and its upper end has a notch 214 adapted to engage a projecting end of the bail 164 when the bar is rotated counterclockwise, as seen in Fig. 3, to the dotted line position. In this position the bail 164 is held up, against the force of springs 156, tending to pull the platen levers 154 down, and printing cannot take place. The lower arm 215 of lever 211 has attached thereto a tension spring 216, the forward end of which is secured to the frame to normally hold lever 211 in its inoperative position against the shaft 155 which serves as a stop to limit rotation thereof. A rod 217, connected to the lower end of the arm 215, extends to the front of the machine where it is slidably mounted in a bracket 218. A knob or knurled head 219 is provided on the end of the knob for pushing the lever into locking engagement with bail 164 when it is desired to prevent printing.

As previously noted, the cam shaft 137 is driven by the gear 138 through the intermediary of a clutch. This clutch is of the one revolution type and is similar to the clutch described in detail in my prior Patent No. 2,132,413, patented October 11, 1936. As best shown in Fig. 6, it comprises a toothed member 221 secured to gear 138 to rotate therewith, the gear and toothed member 221 being freely mounted for rotation with respect to shaft 137. A cooperating toothed member 222 is slidably mounted on shaft 137 but is constrained to rotate therewith, as by a spline or a key, as well understood in the art. A collar 223 is fixed to the shaft 137 as by a set screw 224 and a compression spring 225 is interposed between the collar and the toothed member 222 to urge the member 222 into driving engagement with the member 221.

The toothed member 222 is provided with a projecting stud 226 which is adapted to cooperate

with a cam shaped edge portion 227 of a hinged plate 228. As the parts are shown in Fig. 6, the stud 226 advances toward the observer and encounters the cam shaped edge portion 227 toward the close of a cycle of operation. As it does so, cam 227 moves the stud to the right, as seen in Fig. 6, compressing spring 225 and disengaging the clutch elements. At its terminus, the cam 227 merges into a stop shoulder 229 which holds the shaft against further rotation until the stud is released from stop 229 by moving plate 228 away from the clutch elements and allowing the stud to become disengaged therefrom. Plate 228 is pivotally carried on the rod 203, as best shown in Fig. 10. A spring 231 tends normally to hold the plate against the clutch elements but a push rod 232, secured to the lower part of the plate 228, and projecting to the front of the machine, affords a means for releasing the clutch for a cycle of operation. The front end of the push rod is provided with a suitable knurled head or knob 233. When the knob 233 is pushed inwardly, plate 228 swings to the dotted line position shown in Fig. 10, clearing the stud 226 to permit the clutch to engage. Upon release, spring 231 swings the plate 228 back against the clutch elements and the operation of shaft 137 is discontinued upon completion of a complete single cycle. However, the knob 233 may be held in continuously and in this case operation of the shaft 137 will be continued without interruption until release of the declutching mechanism just described.

The mechanism just described requires manual release of the declutching plate 228 for each cycle of operation of the machine. For some types of operation, as where sheets are fed by hand to printing position, this is desirable, but it is normally preferred to feed sheets automatically and it is desirable that operation be automatic and continuous, subject to interruption if there is a failure in the feeding of a sheet to printing position or a card to sensing position. An arrangement for this purpose is shown in Fig. 7 where a solenoid 240 has its plunger 241 connected by a link 242 to the plate 228. Normally, for continuous operation of the machine, the solenoid is activated just before the close of each cycle to draw the plate 228 out of the path of the stud 226 and thereby trip the machine for another cycle. Any interruption in current to the solenoid at this time, however, releases the solenoid plunger so that the spring 231 can draw the plate 228 into position to separate the riving elements of the clutch.

Current may be supplied to solenoid 240 from any suitable source. Preferably a sheet controlled interrupter is incorporated in the electric circuit so that failure to feed a sheet to printing position will cause interruption of current to the solenoid in a manner well known in the art.

The electric circuit may include a pair of electric contacts 250, Fig. 7, which are adapted to be closed periodically as by a cam 251 mounted on a shaft 252 which comprises a part of an automatic sheet feeding mechanism not shown. The cam 251 closes the contacts once each cycle near the end of such cycle to activate the solenoid and withdraw plate 228 to permit the clutch to be engaged for another cycle. Should some other part of the circuit be interrupted at this time, as by failure of a sheet feeding or advancing operation, solenoid 240 is not activated even though contacts 250 are closed and automatic operation will not be resumed until the cause of the interrup-

tion is ascertained and removed. If desired, the sheet feeding mechanism may be similarly controlled by a solenoid activated single revolution clutch, such an arrangement being described in my aforesaid Patent No. 2,342,190.

It is believed that the operation of the single printing unit, will be clear from the foregoing description. Briefly, however, the operation of the machine is as follows:

The feed plate 56 feeds a control member such as a card C from the bottom of a pile thereof to a point where its advance end is positioned under the first feed roller 85. At a properly timed point in the cycle of the machine the feed roller 85 is lowered to advance the card C into sensing position where it is accurately aligned with sensing fingers 111. At this point the conjugate cams 179 and 180 on shaft 137 move the arms 173 and bail 172 away from the printing sectors 151. As this occurs the springs 175, which are individually attached to each of the printing sectors, cause the sectors to follow the bail 172 and through racks 113, 112 they cause the sensing fingers or bars 111 to traverse the card C. As each of the fingers 111 encounters a perforation or other indicia on the card C, further movement is stopped and the finger, and the printing sector 151 geared thereto, are stopped, the printing sector thereby positioning a printing character, corresponding to the position of the indicia on the card C, beneath the inked ribbon IR.

After all the sensing bars 111 have been locked and the printing sectors thereby positioned for printing, the rotating shaft 137 brings the cam 167 to a point where its follower 165A may drop off the abrupt shoulder on the cam. When this occurs, each of the springs 156 draws its associated bell crank 154 down sharply, striking the platen elements 153 against the article to be printed and producing an impression on its lower face from the printing characters through the inked ribbon IR. Subsequently, rotation of shaft 137 restores the platen arms 154 to their raised positions and the conjugate cams 179 and 180 restore the bail 172 and the printing segments 151 and sensing bars 111 to their normal zero positions.

If the machine is manually controlled it must be tripped for each cycle and this is accomplished by the operator pushing in the knob 233. If the machine is automatic, as it usually is, particularly when articles to be printed are fed automatically, the machine is tripped by the solenoid 240 for each operation and its operation is continuous unless and until a sheet fails to be fed properly. The same control may, if desired, be extended to the card feeding system, so that continuous operation is dependent both upon feed of a card and feed of an article to be printed. This arrangement is not shown in the drawings but is believed to be obvious to those skilled in the art, since it involves only the use of conventional sheet detectors along the path of the card feed.

When it is desired to print data more than once on a single sheet, the feed mechanism for control cards C is geared to operate through only one cycle for each sheet. Thus if each sheet is to be printed with the same data at two or at three positions thereon, as might be done in printing checks and stubs, utility bills and stubs, and the like on a single sheet, the feeder for the control cards operates only once for each two or each three operations of the printing and sensing mechanism. Gearing between the shaft 127 and

shaft 34 is appropriately selected for the particular purpose of the machine.

While I have described my invention as being used particularly in connection with perforated control cards and a particular feed means therefor, as well as with sensing bars 111 of a particular type, it will be understood that any type of control or record member which can be sensed mechanically may be employed therein as well as any type of feed means, suitable modifications being made in the sensing means as desired or as more fully pointed out in my aforesaid co-pending application, Serial No. 663,467, now U. S. Patent No. 2,508,603.

Hence, while I have illustrated and described the preferred embodiments of my invention, it is to be understood that these are capable of variation and modification, and I therefore do not wish to be limited to the precise details set forth, but desire to avail myself of such changes and alterations as fall within the purview of the following claims.

I claim:

1. In a printing machine in which a record-carrying card or the like is advanced from a supply station on to a guideway and fed therewith to a station where the record is sensed by a reciprocable sensing means, and in which machine type-carrying means pivotable in position are set up at a printing station in accordance with the extent of sensing movement of the sensing means, and in which machine platen means are actuated after the record is sensed to cooperate with the type-carrying means to print the record on a sheet locatable at the printing station, a power supply means and a clutch means adapted to be driven thereby, a main drive shaft adapted to be driven by the clutch means, a second shaft driven by the drive shaft, eccentric means at one end of the second shaft for reciprocating a feed means adapted to advance a record-carrying card from the supply station on to one end of the guideway, a feed roller at the said one end of the guideway normally in position to engage a card advanced from the supply station to feed the card to the sensing station, means on the second shaft for raising the feed roller out of engagement with the so-advanced card, a stop means at the sensing station for intercepting the path of the so-fed card, means on the second shaft for raising the stop means out of the path of the so-advanced card after the record thereon has been sensed, an oscillatable bail member at the printing station normally bearing against the type-carrying means to hold the same in a non-printing position while the so-advanced card is being fed to the sensing station, cam means on the main drive shaft for rocking the bail member away from and toward the type-carrying means whereby the type-carrying means are, respectively, free to be set in printing position and to be restored to non-printing position, a second bail member at the printing station normally holding the platen means in non-actuated position, a second cam means on the main drive shaft for rocking the second bail member away from and toward the platen means whereby the platen means are, respectively, free to be actuated and to be restored to non-actuated position, and means for disengaging the clutch means whereby the machine is disabled.
2. A printing machine comprising a supply station from which a record-carrying card or the like is to be advanced on to a guideway, said guideway leading to a sensing station, a recipro-

cable sensing bar at the sensing station adapted to sense the record on said card, printing means pivotable in position at a printing station and operatively connected to the sensing bar and adapted to be set up in accordance with the extent of sensing movement of the sensing bar, actuatable platen means at the printing station adapted to cooperate with the printing means to print the record on a sheet locatable therebeneath, a power supply means, a clutch adapted to be driven by the power supply means, a main drive means adapted to be driven by the clutch means, a shaft driven by the main drive means, a feed plate at the supply station adapted to engage the trailing end of a record-carrying card thereat to advance the same on to the guideway, means operated by the shaft to reciprocate the plate toward and away from the supply station, a feed roller adjacent the supply station at one end of the guideway in position to engage the so-advanced card to feed the same to the sensing station, means operated by the shaft to raise and lower the feed roller relative to the said one end of the guideway, stop means in the guideway at the sensing station adapted to intercept the path of the so-fed card, means operated by the shaft to raise and lower the stop means relative to the guideway, an oscillatable bail member at the printing station for engaging an extension of the printing means, cam means on the main drive means for withdrawing the bail member away from engagement with respect to the printing means when the so-fed card is at the sensing station, cam means on the main drive means for moving the bail member into engagement with the printing means after the record has been printed to restore the printing means to non-printing position, a second bail member at the printing station normally bearing against the platen means to hold the same in a non-actuated position, cam means on the main drive means for withdrawing the second bail member away from engagement with respect to the platen means after the printing means have been set up, and cam means on the main drive means for moving the second bail member into engagement with the platen means to restore the platen means to non-actuated position after the record has been printed.

3. In a printing machine comprising a printing means and a platen means mounted for movement between printing and non-printing positions at a printing station, a supply magazine for record-containing cards or the like, a guideway extending from one end of the supply magazine to a sensing station and along which said cards are to be sequentially fed, reciprocable plate means at the other end of the magazine for advancing one of said cards therefrom on to the guideway, feed means and a guideway for advancing a sheet to be printed to the printing station, reciprocable sensing means at the sensing station for sensing the record on a record-containing card thereat, the printing means being mounted at the printing station for movement to and from printing and non-printing positions, the printing means being connected to the sensing means for movement to printing positioning in accordance with the extent of sensing movement of the sensing means, a power supply, a drive means, a driven means, a clutch adapted to couple the drive means with the power supply, the reciprocable plate means being linked to the driven means, a stud fixed to the clutch for rotation therewith, means normally holding the

clutch engaged whereby power is transmitted to the drive and driven means, a pivotable plate contiguous to the clutch and having a cam edge adapted to be urged into the path of the rotatable stud to effect disengagement of the clutch to thereby disable the drive and driven means, means operable to detect failure to feed a sheet or card and to thereupon cause the pivotable plate to be moved into the path of the rotating stud, a feed roller adjacent the said one end of the magazine in position to be lowered to engage a card advanced from the magazine to the guideway to feed the card to the sensing station, means operated by the driven means to raise and lower the feed roller relative to the guideway, a stop element in the guideway at the sensing station in position to be lowered into the path of the so-fed card prior to arrival of the card at the sensing station, means operated by the driven means to raise and lower the stop element relative to the guideway, a bail member at the printing station normally holding the printing means in non-printing position, means operated by the drive means to withdraw the bail member relative to the printing means when a record-containing card is in position at the sensing station, a second bail member at the printing station normally holding the platen means in said non-printing position, means operated by the drive means to withdraw the second bail member relative to the platen means after the printing means are located in printing position, and means carried by the drive means to effect restoring action of the bail members after printing the record at the printing station.

4. A printing machine comprising; a printing station comprising a printing means in the form of a plurality of individual printing sectors movable from a non-printing to a printing position, a plurality of platen means for cooperating with the printing means and being movable from a non-impressing to an impressing position to effect printing of a record on a sheet feedable to the printing station, a supply magazine for record-carrying cards, a sensing station for the card, means for feeding the cards sequentially from the magazine and along a guideway to the sensing station, reciprocable sensing means at the sensing station adapted to be moved across the card to be sensed to the extent of the record carried thereon, the printing means and the sensing means being directly connected whereby the printing means are adapted to be set in accordance with the extent of sensing movement of the sensing means, a releasable bail member at the printing station normally bearing against each of the printing sectors to hold the same in non-printing position, a second releasable bail member at the printing station normally bearing against the platen means to hold the same in the non-impressing position therefor, a power supply and a main drive shaft connected thereto, cam means on the drive shaft timed, respectively, to withdraw the first bail member relative to the printing means when a card is in position to be sensed at the sensing station and to withdraw the second bail member relative to the platen means after the record has been sensed and the printing means set in accordance therewith, and other cam means on the drive shaft to restore the bail members relative to the printing and platen means after printing has been effected at the printing station.

5. In a printing machine, a power supply and a main drive shaft, a one-revolution clutch for

coupling the power supply and the drive shaft, printing means and cooperating platen means each movable from a non-printing to a printing position, bail members for holding said printing and platen means in non-printing position and for restoring the same from printing to non-printing position, means on the drive shaft for oscillating the bail members toward and away from the printing and platen means in timed relation, one with respect to the other, a guideway along which articles are to be sequentially fed to another station in the machine, a driven shaft, a stop element in the guideway at said other station for engaging the articles thus fed, a feed roller in the guideway for advancing articles along the guideway to the stop element, said roller and stop element normally being held out of engagement with the articles in the guideway, means on the driven shaft for raising and lowering the feed roller and stop element in timed relation one with respect to the other, and means to disengage the clutch when there is a failure to advance an article to said other station, said means on the driven shaft being effective to lower the feed roller and stop element prior to the said means on the drive shaft being effective to oscillate the bail members away from the printing and platen means.

6. In a cyclic operable record printing machine in which a record card to be sensed is fed along a guideway to a sensing station prior to printing the record at a printing station, and in which machine the printing means are in the form of individual pivotably mounted printing sectors adapted to be set in printing position in accordance with movement of sensing means at the sensing station, means for feeding a sheet to be printed to the printing station, means for moving the printing sectors from a non-printing to a printing position, a plurality of platen elements corresponding in number to the printing sectors and being movable from non-printing to printing position, a main drive shaft, an oscillatable bail member for engaging each of the printing sectors to hold the same in non-printing position, an oscillatable bail member for holding the platen elements in non-printing position, cam means on the drive shaft for withdrawing the first bail member relative to the printing means immediately after a record card is in sensing position at the sensing station, cam means on the drive shaft for withdrawing the second bail member rela-

- tive to the platen means after the printing means are set in printing position, means to actuate the platen elements from non-printing to printing position, and other cam means on the drive shaft for restoring the bail members relative to the printing and platen means after the record has been printed.
7. In a printing machine in which articles bearing records are sequentially fed along a guideway to a sensing station where reciprocable bars are adapted to sense the record and to set up individual type sectors in printing positions corresponding to the record sensed, and in which machine platen elements movable to a printing position and corresponding in number to the printing sectors cooperate with the so-set type elements to print the record on a sheet locatable at a printing station, a main drive shaft, a driven shaft connected to the driving shaft, a feed roller in the guideway adapted to advance the articles sequentially therealong to the sensing station, a stop element at the sensing station against which the leading end of each article is adapted to abut in sensing position, cam means on the driven shaft for raising and lowering the feed roller and stop element in timed relation one with respect to the other, a bail for normally holding the printing sectors out of printing position until an article is located at the sensing station, means on the drive shaft effective to disable the bail when an article is located in sensing position, another bail normally holding the platens out of printing position, means on the drive shaft for disabling said other bail when the printing sectors are set up in printing position, means on the drive shaft to effect restoring action of said bails relative to said printing sectors and platen elements, and means to move the printing sectors and platen elements to printing position and operable upon disabling of the corresponding bails.
